Application September 20, 1946, Serial No. 133,474
In Australia July 1, 1946

Term of patent 14 years

(Cl. D31—19)

To all whom it may concern:

Be it known that I, Edmund Frederick Wilks, British Subject, residing at 18 Portland Street, Dover Heights, near Sydney, New South Wales, Australia, have invented new, original, and ornamental Design for Stove Casing, of which the following is a specification, reference being had to the accompanying drawing, forming part thereof:

Fig. 1 is a front elevation, Fig. 2 is a side elevation and Fig. 3 is a top plan view of a stove casing embodying my new design.

The side of the stove not shown is substantially plain with the exception of a hole for a flue.

I claim:

The ornamental design for a stove casing, substantially as shown and described.

EDMUND FREDERICK WILKS.
